UNITED STATES PATENT OFFICE

ARTHUR H. ADAMS, OF YONKERS, NEW YORK, ASSIGNOR TO F. LEO CRILLY, OF LONDON, ENGLAND

METHOD OF REENFORCING CINEMATOGRAPH FILMS

Application filed November 25, 1929. Serial No. 409,737.

This invention relates to the art of reenforcing cinematograph film and has as an object the provision of suitable reenforcing strips secured along the edges of the film and the provision of a method of securing said reenforcing strip to the film.

Other objects of the invention will be apparent to those skilled in the art from the following description.

10 A preferred embodiment of the invention will now be described, reference being made to the accompanying drawings, wherein:

Figure 1 is a plan view of a reenforcing strip after the first operation has been performed;

Figure 2 is a longitudinal section taken on the line 2-2 of Figure 1;

Figure 3 is a diagrammatic view of the reenforcing strip positioned in apparatus 20 for performing the first operation on it;

Figure 4 is a plan view of the film strip after one series of apertures has been punched in it;

Figure 5 shows apparatus for punching 25 one series of apertures in the film;

Figure 6 shows apparatus for punching another series of apertures in the film;

Figure 7 is a plan view of the film with both series of apertures punched in it ready 30 for assembly with the reenforcing strips.

Figure 8 shows apparatus for assembling the film and reenforcing strip;

Figure 9 shows apparatus for piercing the projection formed on the reenforcing strip;

Figure 10 shows the position of apparatus 35 after the piercing operation has been completed;

Figure 11 shows apparatus for turning the burrs formed by the piercing operation;

Figure 12 shows apparatus for clenching the burrs;

Figure 13 shows the completed film and reenforcing strip;

Figure 14 is an enlarged bottom plan view 45 of the clenching burrs;

According to the preferred embodiment of the present invention, the film and the reenforcing strips are first prepared separately and are thereafter assembled and secured together. For convenience in description, the

method of preparing the reenforcing strips will first be described, then the method of preparing the film and finally the method of assembling and securing the two together.

As is well understood in the art, cinematograph film shrinks considerably as it ages. For example, in certain films which have been measured, it has been found that within a period of a year shrinkage as great 1.5% or even 2% may occur. This fact gives rise 55 to a special problem when reenforcing with metal reenforcing strips as in the preferred embodiment herein, for obviously, since metal does not shrink with age there will be a tendency (assuming equal lengths of metal 60 strip and film to have been originally secured together) for the metal to buckle slightly as film shrinkage occurs.

In order to minimize this tendency insofar as possible, it is proposed, according to the 70 invention herein, to assemble the strips and the film in definite dimensional relationship based on the shrinkage factor of the film.

If for every given unit of length of the film at the time of assembly a length of reenforcing strip is selected which is shorter than the film but longer than the expected length of the film after shrinkage has occurred, it will be apparent that when secured together in this relationship as shrinkage occurs the 75 unit length of film will gradually approach the length of reenforcing strip, and then as still more shrinkage occurs, will gradually become shorter than the strip. In no case, 80 however, will the discrepancy between the two unit lengths be as great as it would be if equal lengths of film and strip were assembled without regard to the shrinkage condition of the film. By proper selection of the 85 relationship in which the two are originally assembled the discrepancy can be made very small during the major portion of the useful life of the film.

For example, if the film is new and it has 95 been determined that a given unit will shrink 1% in two months but only 2% in a year it will be apparent that if a unit of strip 1% or thereabouts shorter than the film is assembled therewith, the discrepancy in length for 100

the major portion of the year will be very slight.

For convenience, the distance between the center of the sprocket holes or perforations 5 may be taken as unit lengths, these holes being punched in the film at standard distances during its manufacture.

As the first step then in the preparation of the reenforcing strip, referring to Figure 10 1 and 3 the said strip may be punched with sprocket holes 1 spaced at distances selected as previously described with relation to the shrinkage condition of the film with which it is to be later assembled. This operation 15 may be conveniently performed by means of the punches 2 which cooperate with die 3 to form the perforations of the desired size and shape.

At the same time suitable projections 4 20 which are used, as hereinafter explained, for securing the strip to the film may be embossed in the strip. These projections are preferably arranged in a row, close to the edge of the strip and outside the row of 25 sprocket holes and their spacing being made with respect to the said holes. Thus, in the preferred embodiment illustrated a projection is aligned transversely with the center of each sprocket hole and a second projection 30 is spaced midway between the sprocket hole centers.

If desired, an additional set of projections 35 may also be embossed in the strip, these projections being located inside the projections 4 and intended to secure the inside edge of the strip against displacement. Preferably the 40 said projections are also located midway between sprocket hole centers.

As illustrated in Figure 3 of the drawings, 45 punches 6 for forming the projections 4 and 5 may be associated with the punch 2 in proper relationship to provide the desired spacing. And a spring-biased presser-foot 7 may be associated with the said punches in order 50 to hold the work firmly while being punched. The projections which are formed in the strip are preferably in the form of small rounded domes as illustrated in Figures 2 and 9.

In the preparation of the film, it is desired 55 to provide perforations suited to receive the projections 4 and 5 of the strip, said perforations to be located in the same relative positions with respect to the sprocket holes already punched as the projections occupy with 60 respect to the sprocket holes in the strip, although due to the difference in unit lengths the absolute distances between perforations will be slightly different from the distances between projections.

For convenience (referring to Figures 4 60 and 5) the perforations 8 may be made first, after which (referring to Figures 6 and 7) the perforations 9 may be made. The perforations 8 are preferably located by reference to opposite edges of each sprocket hole.

This may be conveniently accomplished by providing a pilot finger 10 having beveled faces 11 which engage the edges of the sprocket holes and thus center the film for the punching operation. After being centered, the film may be held by the spring-biased presser-foot 12 which holds the film until punched by the punch 13. Figure 4 shows the film strip after the holes 8 have been punched.

The perforations 9 are also preferably located by reference to the edges of the sprocket holes, but instead of using opposite edges of a single hole as previously described, adjacent edges of adjoining holes are used. Thus, a pilot finger 14 (as seen in Figure 6) having inside beveled faces 15 is provided which centers the film by engaging edges 16, 16' of the sprocket holes. After the film is centered it may be held by the spring-biased presser-foot 17 until punched by punches 18. In this manner it will be observed that the perforations 9 will be accurately located midway between the sprocket hole centers.

After being thus prepared the strip and film are ready for assembly. For this purpose, as illustrated in Figure 8, the two strips are fed together in face-to-face relationship in such a manner that the projections embossed in the strip enter the perforations in the film successively. As will be understood, although the film perforations are spaced differently from the strip projections, the difference is sufficiently small to permit the projections to center themselves in the perforations when engaged successively, thus causing a slight buckling of the film between successive perforations.

After assembly the projections are punctured (Figures 9 and 10) by needle points 19 which pierce the metal and bend back burrs 20, the assembled film and strip being held meanwhile by the presser-foot 21.

Subsequently, the burrs 20 are bent outwardly by plunger 2 having beveled edges 23 and finally the burrs are flattened and pressed into the film by pressure plate 24 which bends the outwardly flared burrs around the edges of the film perforations, thus firmly securing the two together.

What I claim is:

1. The method of longitudinally reenforcing a cinematographic film strip with a metal strip, which comprises, centering the film strip on a sprocket hole and punching an aperture in line with the sprocket hole, centering the film strip on adjacent edges of adjoining sprocket holes and punching an aperture between the sprocket holes, punching projections on a reenforcing strip corresponding to the apertures of said film strip and in the same operation punching sprocket holes in said reenforcing strip, assembling said strips with said projections in said apertures, piercing said projections to form burrs, and bradding said burrs to secure said

- strips firmly together, substantially as set forth.
2. A cinematographic film strip comprising, a film strip and a reenforcing strip secured thereto by a plurality of tubular burrs formed of the reenforcing strip bradded upon the film strip, said burrs being located near but not associated with the sprocket holes of the strips.
- 10 3. A cinematographic film strip comprising in combination, a film strip having sprocket holes along one edge and a reenforcing strip secured thereto along the edge, said reenforcing strip being provided with 15 sprocket holes mating with the sprocket holes of the film strip and rivet means securing said strips together at a plurality of points outside the line of said sprocket holes and at other points within the line of the sprocket 20 holes.
4. The method of securing a reenforcing strip to a cinematographic film strip which comprises forming apertures on the film strip, forming dome-shaped projections on 25 said reenforcing strip, positioning said projections in said apertures, piercing said projections to form tubular burrs extending through said film strip, spreading said burrs by a conical die, and bradding said burrs by 30 a flat die.
5. The method of preparing a cinematographic film strip for the assembly therewith of a reenforcing strip, which comprises, positioning said strip by a tapered member 35 engaging the edges of a single sprocket hole, holding the strip by a spring biased presser-foot, and punching an aperture in the film in line with the hole while the strip is held by the presser foot.
- 40 6. The method of preparing a cinematographic film strip for the assembly therewith of a reenforcing strip, which comprises positioning said strip by a tapered member engaging the adjacent edges of adjoining 45 sprocket holes, holding said strip by a spring biased presser-foot and punching apertures in said film intermediate said holes while the strip is held by the presser foot.
7. The method of preparing a reenforcing 50 strip for a cinematographic film strip, which comprises holding said reenforcing strip by a spring-biased presser-foot and punching a sprocket hole and a plurality of dome-shaped projections from said strip while so held.
8. The method of reenforcing a film strip which comprises, punching rivet holes adjacent each sprocket hole, punching corresponding dome shaped projections on a re-enforcing strip, superimposing said strips to place the projections in said holes, piercing said projections to extrude the tubular walls thus formed through said holes, and subsequently turning the ends of said walls on 55 60 65 70 75 80 85 90 95 100 105 110 115 120 125 130
- the other side of the film strip to secure the reenforcing strip thereto.
9. As an article of manufacture, a flexible film strip reenforced by a flexible metal strip along its edge, said metal strip being attached to said film strip by minute burrs punched out of the metal strip itself extending through the film strip and riveted upon the opposite side of the film strip said burrs being located near but forming no part of the sprocket holes of the strips.
10. The article as set forth in claim 9 which is further characterized by the fact that for each sprocket hole there is one or more rivets.
11. The article as set forth in claim 9 which is further characterized by the fact that the rivets are located between each pair of sprocket holes.
12. The article as set forth in claim 9 which is further characterized by the fact that the rivets are located between each pair of sprocket holes, there being two rivets on the same transverse line, one near the outer edge of the strips and another near the inner longitudinal edges of the sprocket holes.
13. As an article of manufacture, a film strip reinforced on its outer edges by a re-enforcing strip secured thereto by small rivets between each sprocket hole, the rivets being so narrow longitudinally of the film strip as to permit free flexing of the material between each pair of sprocket holes.
14. As an article of manufacture, a film strip reinforced on its side edges by a reenforcing strip which is secured thereto at frequent intervals by rivets, the rivets being much smaller than the sprocket holes of the strip to permit free flexing of the composite strip over a small radius as required in projection.
- In testimony whereof, I have signed my name to this specification this 6th day of November 1929.
- ARTHUR H. ADAMS.
